United States Patent Office.

JORDAN L. MOTT, OF MOTT HAVEN, NEW YORK.

A.

Design No. 2,619, dated April 16, 1867.

DESIGN FOR A WASH-STAND.

The Schedule referred to in these Letters Patent and making part of the same.

TO ALL WHOM IT MAY CONCERN:

Be it known that I, J. L. MOTT, of Mott Haven, in the county of Westchester, and State of New York, have invented a new and useful Design for Wash-Stands; and the following is a full, clear, and exact description of the same, reference being had to the accompanying drawings, making a portion of this specification, in which—

Figure 1 is a front view of a wash-stand made according to my design.

Figure 2 is a horizontal transverse section of the same.

Similar letters of reference indicate corresponding parts in both figures.

The front, A, of the stand is formed in its general outline upon a half circle, as shown in fig. 2, and the door at the central part thereof is formed with a panel, *a*, surrounded by a raised moulding, *b*, the shape of which may be more clearly understood from the cross-section, fig. 2. The form of this panel is rectangular, except in this, that its upper end is arched, as shown in fig. 1, and formed centrally thereon is an oval convex figure, *a***, having a raised band, *b***, extending diagonally across it, and surrounded by a raised ornamental margin figure, *c***, as shown in fig. 1. Formed upon either side of the door just mentioned, is a similar panel, *d*, which is, in like manner, surrounded by a moulding, *e*, which corresponds to the moulding *b*. Another like, but narrower, panel, *f*, surrounded by a like moulding, is situated near each edge of the front A, and situated between each of the panels *f* and the contiguous panels *d*, is a broad vertical rib or pilaster, *g*, upon the outer surface of which is a vertical moulding, *h*, the cross-section of which, as in the case of the other mouldings hereinbefore mentioned, is shown in fig. 2. The outwardly projecting pediment A*, corresponds in curvature with the lower edge of the front A, upon which it is formed, and has upon its upper side or edge a moulding, the shape of which is more clearly indicated at *a*', in fig. 1. The forward edge of the top B is shaped to correspond with the outline of the front A, beyond which the said edge projects, and has formed upon it an ogee moulding, *b*'. The centre of this top has formed in it the semispherical bowl *c*', and near each end thereof is a semispherical recess, *d*'. The edge portion of this top, B, is slightly raised, as shown at *e*'. The vertical back-piece C is straight, and is situated at the rear edge of the top, B, and has its upper edge curved, as shown at *a** *b**, and its ends ogee shaped, as shown at *b** *c**, with an ogee moulding formed upon its entire edge.

What I claim as my invention, and desire to secure by Letters Patent, is—

The design and configuration of a wash-stand, herein shown and described.

JORDAN L. MOTT.
